US0D1047611S

(12) **United States Design Patent** (10) Patent No.: **US D1,047,611 S**
(45) Date of Patent: ** Oct. 22, 2024

(54) **INSULATING DEVICE**

(71) Applicant: **YETI Coolers, LLC**, Austin, TX (US)

(72) Inventors: **Roy Joseph Seiders**, Austin, TX (US); **Derek Sullivan**, Austin, TX (US); **Erik Steven Larson**, Austin, TX (US); **Alex Baires**, Austin, TX (US)

(73) Assignee: **YETI Coolers, LLC**, Austin, TX (US)

(**) Term: **15 Years**

(21) Appl. No.: **29/918,692**

(22) Filed: **Nov. 29, 2023**

Related U.S. Application Data

(63) Continuation of application No. 29/825,279, filed on Jan. 31, 2022, now Pat. No. Des. 1,033,160, which is a continuation of application No. 29/783,999, filed on May 17, 2021, now Pat. No. Des. 942,221, which is a continuation of application No. 29/750,198, filed on (Continued)

(57) **CLAIM**

The ornamental design for an insulating device as shown and described.

DESCRIPTION

FIG. 1 is a top, front, right perspective view of an insulating device showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dot-dash lines represent unclaimed boundaries. The zig-zag broken lines represent zipper teeth and form no part of the claimed design. The even-length broken lines form no part of the claimed design.

1 Claim, 7 Drawing Sheets

Related U.S. Application Data

Sep. 11, 2020, now Pat. No. Des. 919,375, which is a continuation of application No. 29/703,040, filed on Aug. 23, 2019, now Pat. No. Des. 896,039, which is a continuation of application No. 29/625,827, filed on Nov. 13, 2017, now Pat. No. Des. 859,934, which is a continuation of application No. 29/553,981, filed on Feb. 5, 2016, now Pat. No. Des. 802,373.
